UNITED STATES PATENT OFFICE

EDWARD ENGEL, OF BLOOMINGTON, ILLINOIS, ASSIGNOR TO MULLINS MANUFACTURING CORPORATION, OF SALEM, OHIO, A CORPORATION OF NEW YORK

WRINGER

Application filed December 2, 1931. Serial No. 578,450.

The object of my invention is to provide an improved mechanism for readily associating and dissociating the two coacting rollers of a wringer.

5 The accompanying drawing illustrates my invention in an embodiment suitable for ordinary household use.

Fig. 1 is a vertical axial section in partial side elevation;

10 Fig. 2 is an end elevation in partial vertical section just inside the end wall of the base or main frame, and

Fig. 3 is a plan on a smaller scale.

15 In the drawing 10 indicates a main frame or base, conveniently formed of sheet metal, and comprising hollow end standards 11, oppositely extending aprons 12, guard wings 13 and an intermediate trough 14 perforated in its bottom at 15.

20 Each end standard is provided, in a common manner, with a vertical guide, open at its upper end for the reception and support of usual bearing blocks 16 of the lower roller 17 and for the reception of usual bearing blocks 18 of the upper roller 19.

The above-described construction is well-known in the art and, in detail, may be varied through a wide range.

25 The upper end of each standard 11 is partially closed by inwardly extending blocks 20, 20, each of which is provided with a vertical threaded perforation 21 within which is screwed the upper threaded end of a depending bolt 22, normally held against rotation in its block 20 by check nut 23.

30 Each bolt is projected through an ear 24 at the lower end of an upwardly extending connector plate 25, one of which lies just inside the outer end wall of one of the hollow standards 11 and the ears 24 normally resting upon the heads 22' of the bolts. The upper end of plate 25 lies between blocks 20.

35 Resting upon each ear 24 is the lower end of a compression spring 26 sleeved over a bolt 22 and initially compressed by an adjusting nut 27 threaded on the bolt.

40 One of the connector plates 25 is vertically slotted at its lower end, between its ears 24 by a slot 30 through which the shaft of the lower roller 17 may project.

In commercial practice both connector plates will be so slotted.

45 Each connector plate 25 is provided, near its upper end, on its inner face with an inwardly projecting pin 31 upon which is preferably rotatably mounted a roll 32.

An upper frame or cross piece 35, conveniently formed of sheet metal and shaped so as to sleeve over the upper ends of standards 11 has journaled therein a rock shaft 40, the ends of which are exposed, and to these ends are connected arms 41 with their outer ends in convenient access by the operator. The outer ends of the two arms 41 are connected by a cross bar 42. This cross bar 42 may be omitted if desired.

55 Secured to rock shaft 40, near each end and within the cross head 35, is a cam plate 45, provided with a segmental arcuate cam flange 46 adapted, by oscillation of rock shaft 40, to take under the adjacent roll 32 and thus connect the cross bar 35 with springs 26.

The cam flange 46 may be so formed as to take under rolls 32 without initially stressing springs 26, but in practice these cam flanges are generally so formed that, while their outer ends will pass freely under rolls 32, the intermediate portion of the flange will

60 positively engage the rolls (when arms 41 are in their medial upright positions) so as to place springs 26 under slight initial compression. The precise curvature of the cam flanges 46 may be varied through a wide range and departures from concentricity with the axis of the rock shaft will be ordinary so slight that no special means need be provided for retaining the operating arms 41 in their medial vertical position.

65 Insurance to this end may be provided, in a well-known manner, by providing a shallow notch in the upper face of each cam flange at its middle, (not shown).

70 The cross head 35, near each end, is provided with a transverse bar 50 arranged to form seats for the upper sides of the upper roller bearing blocks 18, the parts being so proportioned that transverse bars 50 will be in engagement with the bearing blocks 18 and roller 19 will be in engagement with roller 17.

With the parts in the positions shown in the drawing introduction of material between the rollers 17 and 19 will displace roller 19 upwardly, thus causing bearing blocks 18 to lift transverse bars 50 and the cross head 35, thereby shifting cams 45 upwardly against rolls 32 and stressing springs 26.

Rolls 32 may be properly positioned for 10 coaction with cam flanges 46 by axial adjustment of bolts 22, as will be readily apparent.

The upper end of each connector plate 25 is vertically medially slotted, as indicated at 15 51 to straddle the rock shaft and thus serve to take the lateral thrust of the cam flanges 46 on rolls 32.

Beneath each apron 12 is an outwardly and downwardly inclined drain pan 60 and the gap between the inner edges of these 20 drain pans is bridged by a rocking drain pan 61 provided at one end with a pivot pin 62 slidably projected through an opening in one end wall of the base, and at the other end with a spring pivot pin 63, the outer 25 end of which is slidably projected through an opening 64 in the opposite end wall of the base, the arrangement being such that the spring pivot pin may be readily retracted from engagement with the base and thus permit the tilting drain pan to be readily withdrawn for cleansing.

The drain pan at one end is provided with a forked projection 65, radially distanced from the axis of the pivot pins, and projecting into this fork is a finger 36 carried by a split collar 67 frictionally journaled on the shaft of the lower roller, the two parts of this collar being held in yielding frictional engagement with the shaft by a spring clip 68 of 40 well known form.

By rocking the rock shaft in either direction from its medial position, the cam flanges will be withdrawn from beneath the rolls 32, thereby disconnecting the upper roller 19 45 from the influence of springs 26, and the upper cross-head may then be lifted clear from the base, whereupon the upper roller 19 with its bearings may be extracted. To reassemble the parts, the upper roller is placed on the 50 lower roller with its bearing blocks 18 in the guideways in standards 11. Rock shaft 40 being thrown to one or the other of its extreme position, cross bar 35 may now be sleeved down over the upper ends of standards 11 with its transverse bars 50 overlying the bearing blocks 18, whereupon, by rocking the rock shaft to its medial position, the cam flanges 46 will pass under the rolls 32, thereby tying the upper roller to the springs 26.

60 I claim as my invention:

1. A wringer comprising, a base having hollow end standards, spring means anchored in each of said end standards, a connector plate mounted in each of said standards and 65 associated with the adjacent spring means,

a cross head having abutments for bearing blocks of the upper wringer roller, a rock shaft journaled in said cross head and provided with means external of the cross-head by which it may be manipulated, and projections carried by said rock shaft laterally interlockable in one direction with the connector plates by angular movement of the rock shaft.

2. A wringer comprising, a base having hollow end standards, a pair of depending bolts mounted within each end standard, a coiled spring mounted upon each bolt within the end standard, a connector plate mounted within each end standard and engaging the springs therein, a cross-head having abutments for bearing blocks of the upper wringer roller, a rock shaft journaled in said cross-head and provided with means external of the cross-head by which it may be manipulated, and projections carried by said rock shaft laterally interlockable in one direction with the connector plates by angular movement of the rock shaft.

3. A wringer comprising a base having hollow end standards, a pair of depending bolts mounted within each end standard and axially adjustable therein, a coiled spring mounted upon each bolt within the end standard, a connector plate mounted within each end standard and engaging the springs therein, a cross-head having abutments for bearing blocks of the upper wringer roller, a rock shaft journaled in said cross-head and provided with means external of the cross-head by which it may be manipulated, and projections carried by said rock shaft laterally interlockable in one direction with the connector plates by angular movement of the rock shaft.

4. A wringer comprising a hollow base, a tiltable pan medially mounted in the lower part of said base, and provided with a longitudinally arranged fulcrum, said fulcrum engaging the base at opposite ends of the pan, and at one end comprising an axial element carried by the pan and shiftable relative to the pan and base to laterally interlock the fulcrum with the base and to permit lateral extraction of the pan from the base.

In witness whereof, I have hereunto set my hand at Bloomington, Illinois, this 21st day of November, A. D. one thousand nine hundred and thirty-one.

EDWARD ENGEL.
